Attorney

UNITED STATES PATENT OFFICE.

LIBBIE M. KOEHLER, OF SEATTLE, WASHINGTON.

BODKIN.

Application filed November 11, 1922. Serial No. 600,370.

To all whom it may concern:

Be it known that LIBBIE M. KOEHLER, citizen of the United States, residing at Seattle, in the county of King and State of Washington, has invented certain new and useful Improvements in Bodkins, of which the following is a specification.

This invention relates to improvements in bodkins, and particularly to the means of securing the end of a ribbon in the bodkin.

An object of the invention is to provide a bodkin having a body portion with one end overturned to provide a pivot for a ribbon holding member, between which and the body portion of the bodkin, the end of the ribbon is secured.

This construction enables the ready insertion and securing of the ribbon in the bodkin, by which the ribbon may be quickly inserted in lingerie and like garments having openwork for draw strings and the like.

In the drawings:

Fig. 1 is a plan view of the bodkin.

Fig. 2 is a longitudinal section thereto through.

Fig. 3 is a detail perspective view of the ribbon holding member.

The bodkin is provided with a body portion 1 having one end of reduced width and pointed as indicated at 2. The other end is bent over at 3 and extended back over the body portion at 4, the bent portion 3 being provided with a ribbon receiving slot 5, and the portion 4 being formed with a slot indicated at 6.

A ribbon holding member 7 has a tongue 8 struck out of the body thereof, extended through the slot 6 and bent at 9 back towards the body portion around the end of the overturned end 4 to provide a pivot for the member.

The end 10 of the member 7 is curved downwardly towards the body portion 1, and is adapted to engage the ribbon inserted through opening 5 and hold it against withdrawal by binding it against the body por-

tion 1. The other end is bent laterally at 11, and a spring 12 secured to the overturned end 4 engages the tongue 8 for normally forcing the curved end 10 thereof toward the body 1.

To use the bodkin for applying ribbon to the openwork of lingerie and the like, the end of the ribbon is inserted through the slot 5 and drawn under the curved end 10 of the holding member where it is held by the pressure of the end on the ribbon against the body 1. The bodkin is grasped between the fingers at the overturned end with a finger pressing down on the member 7, so that the ribbon may be more firmly held in the bodkin, and the end 2 is inserted through the openwork, after which the bodkin with the ribbon is drawn through it for threading the ribbon therein in an obvious manner.

The spring 12 may be omitted as the pressure of the fingers on the member 7 is sufficient for holding the ribbon in the bodkin.

What I claim is:

1. A bodkin, comprising a body formed with an overturned end portion, and a ribbon receiving slot in the bend thereof, and a ribbon holding member formed with a tongue extending through a slot in the overturned end for pivotally connecting the member with said end and having a curved end for engaging a ribbon to hold it between said end and the body.

2. A bodkin, comprising a body formed with an overturned end portion, a ribbon receiving slot in the bend thereof, a ribbon holding member formed with a tongue extending through a slot in the overturned end for pivotally connecting the member with said end and having a curved end for engaging a ribbon to hold it between said end and the body, and a spring normally acting to move the member on the pivot and force the curved end toward the body portion.

In testimony whereof I affix my signature,

LIBBIE M. KOEHLER,
